UNITED STATES PATENT OFFICE

OTTO J. MOEHLER, OF NEWARK, NEW JERSEY, ASSIGNOR TO GENERAL ELECTRIC VAPOR LAMP COMPANY, A CORPORATION OF NEW JERSEY

ADJUSTABLE SUPPORT STAND FOR ELECTRIC LAMPS

Application filed December 21, 1926. Serial No. 156,243.

The present invention relates to a stand for a lamp or lamps and more particularly a stand which can be portable, which is adjustable as to height and which is adapted for carrying a source of light which is extended particularly in one direction, and on which the source is adjustable angularly across the line of extension and also angularly in a vertical plane along the line of its extension. The invention more particularly relates to a stand for adjustably supporting mercury vapor lamp tubes.

Various objects and advantages of the invention will be obvious from the following particular description of one form of apparatus embodying the invention or from an inspection of the accompanying drawing; and the invention also consists in certain new and novel features of construction and combinations of parts hereinafter set forth and claimed.

In the accompanying drawings there is shown for purposes of illustration one form of device embodying the invention, in which Fig. 1 is a vertical elevation view of an embodiment of the invention,

Fig. 2 is a vertical elevation view in part section showing details of a part of the apparatus of Fig. 1,

Fig. 3 is a part view in elevation and in part section taken along the line 3—3 of Fig. 2 and looking in the direction of the arrows,

Fig. 4 is an elevation view in part section and in part broken away showing further details of support construction, and

Fig. 5 is an elevation view taken at right angles to that of Fig. 1.

Fig. 6 is a detail view partly in section showing means of electrical connection and disconnection of a line extension.

In the drawings the base 1 which has the four rollers or casters 3 carry the vertical casing 4 mounted with its center off the center of the base and in which are mounted resistances, transformers, and the like used as auxiliary apparatus for mercury vapor arc lamps such as are well known in the art. On its top said casing 4 carries the standard 5 in which is mounted the vertical support 6 in the form of a tube or pipe. Said pipe

6 has formed by sawcuts therein a lip 7 which holds a collar 8 on the upper end of the pipe by extending into the opening 9 in said collar 8. Said collar 8 has an annular shoulder 10 which rests on the upper end of 55 said pipe 6 and also has a boss 12 having an opening therethrough into which is threaded the set screw 14 which extends against the clamping lip 15 formed in pipe 6. Through said collar 8 and into said pipe 6 there extends another pipe standard 18 which is adapted to be clamped at adjusted positions in said pipe 6 by means of said set screw 14 and said lip 15. When the pipe 18 is in the pipe 6 and the set screw 14 is tightened said 60 65 lip 15 will be forced transversely against the side of the pipe 18 to clamp it in position.

Referring particularly to Figures 2 and 3 and also Figure 1 said pipe 18 carries a head 20 having a socket 22 into which the upper 70 end of said pipe 18 fits. Said pipe 18 carries a collar 24 fixed thereabout in a position just below the lower end of said head member 20 and a member 26 fixed to said head member 20 and extending past said collar 24 and turned 75 inwardly underneath the lower face thereof serves to hold said head member 20 on said pipe 18 and yet permit rotational movement of said head on said pipe. In said head member 20 is a chamber 28 through which and 80 through the slide channels 30 and 32 extends the rack member 34 the lower end of which extends into said pipe 18. Into the end of said member 34 is threaded the stud 36 about which is mounted the compression spring 38. 85 A length of tubing 40 mounted about said member 34 has its upper end against the bottom of said opening 22 and has its lower end extending below the bottom of said member 34. A pair of adjusting nuts 42, 42 hold said 90 spring 38 against the washer 44 mounted about said stud 36 and bearing against the lower end of said tubing 40, the upper surface of said washer 44 serving as a shoulder for engaging the shoulder formed about said stud 95 36 at the lower end of said member 34.

On said member 20 is provided a cover 46 for said chamber 28 which is held thereon by the bolts 48. The openings 50 and 52 respectively through said cover 46 and the opposite 100

wall of said head member 20 serve as bearings for the shaft 54 which carries the pinion 56 which is fixed thereto and which meshes with the teeth of said rack member 34. The 5 teeth on said pinion do not extend completely around and a set screw 58 is used for fixing the pinion to the shaft. A set of washers 60, 60 mounted about shaft 54 between cover 46 and pinion 56 serve through the adjustment of said bolts 48, 48 to apply a detaining pressure on the pinion and thereby regulate the ease of movement of these parts. The hand screw 62 which can be tightened against said rack member 34 serves to fix the moving 10 parts of a lamp carried thereby at desired positions.

Said shaft 54 through the arm 66 supports the longitudinal reflector 64 which is mounted radially therefrom and which carries a 20 mercury vapor arc lamp of the long tube type or a plurality of sources of light mounted along the length thereof. In some cases said head member 20 has a lamp and reflector unit mounted on each side thereof. And in some 25 cases the auxiliary apparatus such as is in casing 4 is mounted on both sides of the vertical axis of said standard 5. The adjustable screws 70 and 72 extending through the flange 74 on said head 20 serve through contact with 30 portions of said arm 66 on opposite sides of said shaft 54 to fix the upward and downward limiting positions of movement of said reflector 64 with its lamp. When the lamp and reflector are moved radially on shaft 54 to adjust 35 the position thereof said spring 38 eases the movement and said shims 60 under pressure serve to compensate for variations in the torque of the weight of said lamp and reflector at different radial positions thereof. 40 The position of the lamp and reflector is adjustable vertically by means of said standards 6 and 18 and said set screw 14; is adjustable rotatably in a horizontal plane either on the casters 3, 3 of stand 1 or by the rotation of 45 head 20 on said pipe 18; and is adjustable radially in a vertical plane on said shaft 54.

While I have shown and described and have pointed out in the annexed claims certain novel features of the invention, it will 50 be understood that various omissions, substitutions and changes in the forms, parts and details of the device illustrated and in its operation may be made by those skilled in the art without departing from the spirit 55 of the invention.

Claims:

1. An adjustable support apparatus comprising an upright tube, a head member swiveled on the upper end of said tube, said 60 head member being provided with a slide-way connecting at all rotative positions with the opening of said tube, a rack slidable in said slide-way and in the tube opening, a sleeve in said tube and about said rack bearing 65 against the lower side of said head member,

a compression spring bearing at one end against the lower end of said sleeve and at its other end against a shoulder on said rack, said shoulder being adjustable on said rack for varying the compression of said spring, 70 a load supporting shaft journalled in said head member and a pinion on said shaft and engaging said rack.

2. An adjustable support apparatus comprising a base, an upright tube supported thereby, a head member swiveled on the upper end of said tube, said head member being provided with a slideway connecting at all rotative positions with the opening of said tube, a rack slidable in said slide-way and in said tube opening, a sleeve in said tube and about said rack bearing against the lower side of said head member, a compression spring bearing at one end against the lower end of said sleeve and at its other end bearing against a shoulder on said rack, adjustable means for fixing the position of said rack, a shaft journalled in said head member, said shaft being adapted to support a weight exerting a considerable turning moment 90 thereon, a pinion on said shaft and engaging said rack, and a weight on one side of said base.

Signed at Hoboken, in the county of Hudson and State of New Jersey, this 16th day 95 of December A. D. 1926.

OTTO J. MOEHLER.
